United States Patent Office

Des. 188,983
Patented Oct. 11, 1960

188,983

FLOOR MAT

Samuel Furiness, 731 Lehigh Ave., Union, N.J.

Filed Apr. 25, 1960, Ser. No. 60,301

Term of patent 14 years

(Cl. D9—6)

Fig. 1

Fig. 2

The bottom, side and end of the mat not shown are the same in appearance as the top, side and end shown.

I claim:

The ornamental design for a floor mat, as shown and described.
